UNITED STATES PATENT OFFICE.

IRVING BECKER AND SAMUEL PERELL, OF NEW YORK, N. Y.

DESIGN FOR A PHOTOGRAPH-HOLDER.

52,519.

Specification for Design.

Patented Oct. 8, 1918.

Application filed June 4, 1918. Serial No. 238,222. Term of patent 3½ years.

To all whom it may concern:

Be it known that we, IRVING BECKER and SAMUEL PERELL, citizens, respectively, of Russia and of the United States, residing in New York, in the county and State of New York, have invented a new, original, and ornamental Design for Photograph-Holders, of which the following is a specification, reference being had to the accompanying drawing, forming part thereof.

The figure is a view in elevation of a photograph holder, showing our new design.

We claim:

The ornamental design for a photograph holder, as shown.

IRVING BECKER.
SAMUEL PERELL.
